UNITED STATES PATENT OFFICE.

SUSANNE A. SHAW, OF SAN FRANCISCO, CALIFORNIA.

DESIGN FOR A DOLL TWINE-HOLDER.

Application filed December 26, 1928. Serial No. 29,415. Term of patent 3½ years.

To all whom it may concern:

Be it known that I, SUSANNE A. SHAW, a citizen of the United States, residing in the city and county of San Francisco, State of California, have invented a new, original, and ornamental Design for Doll Twine Holder, of which the following is a specification, reference being had to the accompanying drawings, forming a part thereof.

Fig. 1 is a front elevation of a doll twine holder showing my new design.

Fig. 2 is a plan view of Figure 1.

I claim:

The ornamental design for a doll twine holder as shown.

SUSANNE A. SHAW.
